ATTORNEY

UNITED STATES PATENT OFFICE.

FRANK CARSON, OF ST. LOUIS, MISSOURI.

LOCK-MOUNTED KEY-GUARD.

1,279,983.

Specification of Letters Patent. Patented Sept. 24, 1918.

Application filed March 19, 1917. Serial No. 155,807.

To all whom it may concern:

Be it known that I, FRANK CARSON, a citizen of the United States, residing at St. Louis, State of Missouri, have invented certain new and useful Improvements in Lock-Mounted Key-Guards, of which the following is a specification.

My invention relates to a detachable lock-mounted key guard.

10 The main object of the invention is to provide a novel, improved, and simplified form of device of this nature which may be detachably suspended from a knob of a door lock and engaged with the key of the said lock to secure it in the key-hole against turning and removal from the outside, and a device of this class which may be made, if desired, principally in a single strand of metallic wire.

20 Another object is to provide an article of this kind having a key supporting loop, a suspending loop, an eyelet at the junction of the loops, a latch secured to the eyelet, said loops having engaging hooks, and the latch being adapted to engage one of said hooks.

With the above, and additional objects, such as will hereinafter appear, in view, the invention has been embodied in one preferred form as hereinafter described and 30 illustrated in accompanying drawings:—

Figure 1 is a view showing my improved article in front elevation and in connection with a door knob and key, suggested in dotted lines;

35 Fig. 2 is a side view of the parts of Fig. 1, and

Fig. 3 is a top or plan view of the improved article.

Referring specifically to the drawings, 40 wherein like reference characters designate like or similar parts, I have illustrated a door lock at 4, of which 5 is an operating knob and 6 the key of the lock. This form is to be taken, of course, as conventional 45 since the invention is capable of use with most types of key-operated locks.

The improved article is preferably but not necessarily made principally in one piece as from a strand of metallic wire. This may 50 have a suspending loop 7 adapted to fit over the shank of the door knob 5 in order to position the article and may also have a second loop 8 joined to the loop 7 by means of a coil as at 7'. One end or extremity of 55 the loop 7 terminates in a hook 9 and which hook 9 is engaged or overlapped by a hook

10 forming the termination of a free or resilient arm 11 of the clasp 8. The resilient arm 11 is detachably connected to the hook 9 by means of the hook 10 and when detached, may be passed through the eye of the key 6.

In order to secure loop 7 effectively in place and minimize the chances of detachment of hook 10 from hook 9, I preferably 60 employ a spring or resilient latch arm 13 which is normally urged into the opening of the hook 9 and into engagement with the top of hook 10. One end of the latch 12 may terminate in spring coils at 13 and a lug 14 engaging loop 7 and forming a spring by means of which the latch is connected to the coil or eyelet 7' and urged into engagement with the hook 9. While the spring at 70 13 normally urges the latch 12 into engagement with hook 9, yet it permits vertical and lateral movement of the latch to facilitate its detachment from the hook 9.

In use, the latch arm 13 is detached from engagement with the hook 9 and also the 80 arm 11 at hook 10 is detached from engagement with said hook 9. At this time the loop 7 may be placed over the shank 5, after or before which, as preferred, the key 6 may be suspended from a loop 8 by passing 85 the arm 11 at the hook end 10 therethrough. While the parts are in this position, the article as a whole is adapted to be swung outwardly away from the door or from the interior so that the key 6 may be inserted 90

into the key hole of the lock. After the key has thus been inserted, the latch arm 11 is operated so that the hook 10 will engage the hook 9 after which the latch arm 13 is operated to extend into the hook 9 and 95 on top of the hook 10. As a result, arm 13 will serve as an abutment to engage the lock parts and limit the swinging movement of the device as a whole and prevent such movement as will permit the key 6 to be 100 dislodged from the key hole. Thus the key at night may be fastened in the key hole and cannot be dislodged by unauthorized persons endeavoring to remove the key and "pick" the lock. In order to remove the 105 key, it is merely necessary to dislodge the latch arm 13 from the hook 9 as well as the hook 10 and then slide the key off of the arm 11.

Since merely the preferred embodiment 110 of the invention has been illustrated and described, it is to be understood that changes

in the details of construction may be resorted to without departing from the spirit and scope thereof.

I claim:

- 5 1. A key guard composed of a single piece of wire and having a suspending loop formed at one end thereof, a key supporting loop formed at the opposite end thereof, means for uniting the free ends of the said loop, a coil between the loops, and means mounted on said coil for engaging the loop uniting means.
- 10 2. A key guard composed of a single piece of wire and having a suspending loop formed at one end thereof, a key supporting loop formed at the opposite end thereof, hooks at the free ends of said loops for engaging each other, a resilient member pivotally mounted at a point opposite said hooks, said resilient member being adapted to lock the free ends of the loops when the hooks are in engagement with each other.
- 15 3. A key guard composed of a single piece of metal having loops formed at opposite ends thereof, one of said loops acting as a suspending means for the entire structure, the other of said loops acting as a supporting means for a key, a coil formed between each of said loops, a latch member coiled
- 20
- 25

around said coil, said latch member being adapted to securely hold the free ends of the loop from disengagement.

4. A key guard having a suspending loop terminating in a hook at one end, a loop to suspend a key, a coil joining said loops, a latch cooperating with said hook to fasten the device against sufficient movement to remove the key from its lock, and said latch having a coil spring portion mounted on said coil.

40 5. A key guard having a suspending loop terminating in a hook at one end, a key suspending loop, a coil at the junction of and integral with said loop, said key suspending loop having a resilient arm terminating in a hook to engage the first mentioned hook, a latch entering the first mentioned hook, and engaging the second mentioned hook, said latch having spring coils, and said spring coils being connected to the first mentioned coil.

45 In testimony whereof I affix my signature in presence of two witnesses.

FRANK CARSON.
